UNITED STATES PATENT OFFICE.

LANSING ONDERDONK, OF NEW YORK, N. Y., ASSIGNEE TO UNION SPECIAL MACHINE COMPANY, OF CHICAGO, ILLINOIS, A CORPORATION OF ILLINOIS.

FEEDING MECHANISM FOR SEWING-MACHINES.

1,115,096.

Specification of Letters Patent.

Patented Oct. 27, 1914.

Application filed June 3, 1904. Serial No. 211,066.

To all whom it may concern:

Be it known that I, LANSING ONDERDONK, a citizen of the United States, residing at New York, Manhattan borough, in the county of New York, State of New York, have invented certain new and useful Improvements in Feeding Mechanism for Sewing-Machines, of which the following is a description, reference being had to the accompanying drawing and to the letters and figures of reference marked thereon.

My invention relates to improvements in feeding devices for sewing machines. So far as certain portions of the feed are concerned, the arrangement is the same as shown on the Union Special interlock machine, which feed is illustrated in detail in the patent granted to Russel G. Woodward on the 24th day of October, 1903, No. 802,789, said patent relating to an arrangement of an inclined pivoted feed dog with certain adjustment for shifting the feed dog on its pivot to vary the angle of inclination at which it engages and feeds the goods. This arrangement of inclined feed dog is for the purpose of crowding a portion of the goods in advance of the needle up to the same, thereby preventing puckering of the fabric after the stitches have been placed therein.

The present invention embodies in the main, an additional feature for varying the height of said pivoted feed dog, whereby a greater or less amount of feeding surface thereof may, in the upward movement of said feed dog come above the surface of the cloth plate.

The invention therefore, consists in the matters hereinafter described and referred to in the appended claims.

It is illustrated in the accompanying drawings, in which—

Figure 1 is a perspective view looking toward the front of the machine of a portion of the sewing machine embodying my invention; Fig. 2 is a transverse section through the machine, showing the feeding mechanism and the means for adjusting the feed dog in side elevation. Fig. 3 is a transverse section showing the feed dog and feed bar from the opposite side from Fig. 2, with certain parts in section to show the vertical adjusting device. Fig. 4 is a front view of a portion of the sewing machine with the parts broken away illustrating the

eccentric arrangement for imparting the forward and backward movement to the feed dog; Fig. 5 is a sectional view illustrating the eccentric which imparts movement to the feed dog and illustrating also the flanged disk secured on the main shaft to which said eccentric is adjustably connected. Fig. 6 is a cross section illustrating details of said adjustment.

In these drawings, A represents a portion of the bed plate of a sewing machine embodying the invention; B, is the needle bar; C, the presser bar; D the presser foot; E the cloth plate; F the driving shaft.

The feeding mechanism herein shown, includes a feed bar which is made in two parts e and e'. The feed bar e' is pivoted to the rocking frame I. Said feed bar carries the usual fork i, the lower flange of which k, engages the under side of a cam K on which the feed bar e' rests. As the cam K is rotated by the main shaft F, the feed bar e' will be moved up and down. The rocking frame I is connected by means of a link I' with the eccentric strap G', which co-operates with the eccentric G on the main shaft. Said eccentric G is adjustably connected to the flanged collar H, which in turn is secured to the shaft F. The eccentric G as herein shown is secured to the flange of the collar H by means of bolts, a, a'. The bolt a passes through a slot b, in a flange carrying the eccentric. The opening through the eccentric is slightly larger than the diameter of the main shaft, so that by loosening the bolt a, the eccentric may be shifted laterally of the shaft and the throw thereof varied. The portion e of the feed bar is also pivoted to the rocking frame I and is adjustably secured to the portion e' of the feed bar by means of the screw stud L. The feed bar e is pivoted to the feed bar e by a pivot pin d, and at its lower end has a vertical slot connection f, with a rounded head g on the end of the rod h, which is screw threaded into a sleeve carried by the upper portion of the fork i. By turning the rod h, it will be noted that the angle of inclination of the feed dog e is varied. This means of adjustment is substantially the same as that shown in the patent of Woodward above referred to.

To provide for a vertical adjustment of the feed dog to vary the amount of feeding surface with which the goods are engaged,

the upper feed bar *e* which carries the feed dog *c*, is provided with an opening *m*, through which passes a screw stud *L*, which at its lower end screws into the lower feed bar *l*. This screw stud *L* passes through a plate *M* secured by screws *n* to the upper feed bar *e* and carries between the plate *M* and the lower feed bar *e'* the collar *o* which as the screw *L* is turned to withdraw it from 10 the bar *l* will bear against the plate *M* and positively raise the upper feed bar *e* and thereafter the feed dog *c*. This is permitted by means of the vertical slot connection between the ball *g* and the lower end of the 15 pivoted dog *c*. This screw *L* has its upper end substantially flush with the top of the cloth plate extending into an opening in the same, so that it is readily accessible to the operator for adjustment. I have herein shown 20 the forward part of the feed dog as provided with a limited number of teeth which are arranged on a downwardly curved or inclined surface, the purpose of this being to prevent the fabric when placed in the machine, from striking against the wall of the feed dog. This, however, is not of my invention, and I do not claim the same. It will readily be seen that by adjusting the vertical position of the feed dog *c* relative to 25 the work support, that a greater or less amount of the feed dog will engage the material in advance of the needle before the feeding stroke takes place, and thereby, the amount of gathering in of the material, may 30 be varied.

Having thus described my invention, what I claim and desire to secure by Letters Patent is:—

1. A feeding mechanism for sewing machines comprising a feed bar, a feed dog pivoted thereto on an axis transverse to the direction of feed, means for adjusting said feed dog on said axis to vary the angle of inclination at which said dog engages 40 the goods, and means for positively adjusting the feed bar vertically to vary the amount of feeding surface with which the goods are engaged, substantially as described.

50 2. The combination with a supporting bar, and upper feeding bar, a feed dog pivoted to the upper feed bar with means for adjusting the angle of inclination at which it engages the goods, of means for positively adjusting the same vertically, comprising a screw secured to the supporting bar, and passing through the upper feeding bar with connections between said screw and the upper feeding bar to cause the same 55 to be moved vertically as the screw is turned, substantially as described.

3. In a feeding mechanism for sewing machines, comprising two feed bars pivoted upon a common frame, the upper one resting 60 65 upon the lower, a feed dog pivoted to

the upper bar and means for swinging the feed dog on its pivot to vary its angle of inclination and means for adjusting the upper feed bar with respect to the lower, and means for operating said common frame substantially as described. 70

4. In a feeding mechanism for sewing machines, comprising two feed bars pivoted upon a common frame, and the upper one resting upon the lower, a feed dog pivoted to the upper bar and means for swinging the feed dog on its pivot to vary its angle of inclination and means for adjusting the upper feed bar with respect to the lower, comprising a screw stud passing through 75 the upper feed bar and into the lower, a plate surrounding said screw stud and secured to the upper feed bar and a collar upon said screw stud bearing at its upper surface upon the under side of said plate, and means for operating said common frame substantially as described. 80

5. In a feeding mechanism for sewing machines, comprising two feed bars, a feed dog pivoted to the upper bar, and means for swinging the feed dog on its pivot to vary its angle of inclination, and means for adjusting the upper feed bar with respect to the lower; means for supporting and operating the feed bars substantially as described. 85

6. In a feeding mechanism for sewing machines, comprising two feed bars pivoted upon a common frame, and the upper one resting upon the lower, means for operating 90 said common frame a feed dog pivoted to the upper bar, and means for swinging the feed dog on its pivot to vary its angle of inclination, and means for adjusting the upper feed bar with respect to the lower, comprising a screw stud passing through 95 the upper feed bar and into the lower, a plate surrounding said screw stud and secured to the upper feed bar and a collar upon said screw stud bearing at its upper surface 100 upon the under side of said plate. 105

7. The combination with a work support, of a feeding mechanism including a two part feed bar, a feed dog carried by one of said parts, said feed dog having a feeding 110 surface downwardly and rearwardly inclined in the line of feed relative to the work support, means for varying the angle of the feed dog relative to the work support, means for adjusting the feed dog and one part of the feed bar relative to the work support, whereby the amount of feeding surface engaging the material may be varied, and means for operating said feed bars. 115

8. The combination with a work support of a feeding mechanism, including a feed dog inclined to said work support, in a downward direction from front to rear in the line of feed, means for operating said 120 125 130

feed dog and means for adjusting said feed dog bodily vertically, whereby the amount of feeding surface engaging the material, may be varied.

5 9. The combination with a work support of a needle, a feeding mechanism including a feed dog extending from in front of to the rear of said needle, said feed dog being inclined downward relative to the work

10 support from front to rear in the line of feed, means for operating said feed dog and means for adjusting said feed dog bodily vertically, whereby the amount of feeding surface engaging the material may

15 be varied.

10. A sewing machine including in combination a work support, a presser foot, a feeding mechanism, including a feed dog, said feed dog having a feeding surface inclined downwardly and rearwardly in the line of feed relative to said work support,

means for operating said feed dog, and means for adjusting said feed dog bodily vertically, whereby the amount of feeding surface engaging the material may be varied.

25

11. A sewing machine including in combination a work support, a pivoted presser foot, of a feeding mechanism including a feed dog, said feed dog having a feeding surface inclined downwardly and rearwardly relative to said work support, means for operating said feed dog, and means for adjusting said feed dog bodily vertically, whereby the amount of feeding surface engaging the material may be varied.
